REVERSING MECHANISM FOR WASHING MACHINES

John Zimarik, Akron, Ohio

Application April 27, 1946, Serial No. 665,566

9 Claims. (Cl. 74—323)

1

This invention relates to washing machines, and in particular relates to a reversing mechanism for a washing machine of the tumbler-drum type.

An object of the invention is to provide a simple improved reversing mechanism for apparatus of the character described, which is continuously self-operating by rotational movement of the drum to reverse the same after a predetermined number of revolutions in either direction.

Other objects of the invention will be manifest from the following brief description and the accompanying drawings.

Of the accompanying drawings:

Figure 1 is a side elevation, partly broken away and in section, of a washing machine of the tumbler-drum type and having incorporated therein improved reversing mechanism embodying the features of the invention.

Figure 2 is a cross-section taken substantially on the line 2—2 of Figure 1, but illustrating the reversing mechanism in one extreme position of operation thereof.

Figure 3 is a fragmentary view of a portion of the mechanism illustrated in Figure 2, illustrating an intermediate position of operation thereof.

Figure 4 is a view similar to Figure 2 illustrating the mechanism in the other extreme position of operation thereof.

Figure 5 is a fragmentary view taken substantially on the line 5—5 of Figure 4.

Figure 6 is a fragmentary view, partly in cross-section, taken substantially on the line 6—6 of Figure 4.

Referring particularly to Figures 1 and 2 there is illustrated a washing machine of a tumbler-drum type shown in the prior patents to John Zimarik, Numbers 2,272,284 and 2,284,243. The washing machine includes essentially a tumbler-drum 10 mounted on a fixed supporting chuck 11 to rotate about a horizontal axis, the chuck being secured to a vertically extending bracket 12 mounted on a stand or base 13. Adjacent the front of the drum additional support is provided for the same as by means of rollers 14 mounted in brackets 15 secured to the stand 13. The arrangement is such that the front of the drum, in which is provided a clothes supplying and emptying closure 16, is free and unobstructed.

The drum 10 may be rotated on its axis by means of a belt 18 extending around the same and engaged over a pulley 17, slidably but non-rotatably keyed at 20 on a shaft 21 which extends from a reversing gear box 19, the gearing in the latter being driven by means of a suitable electrical mo-

tor 20. The shaft 21 is journaled in spaced bearing bosses 22 and 22a in box 19 to extend in substantial parallelism with the axis of drum 10.

A driving shaft 23 from motor 20 extended into the box 19 has a worm screw 24 thereon, meshed with a worm wheel 25 rotatably received on the shaft 21. Integral with the worm wheel is a bevel gear 26 arranged in spaced relation to a similar oppositely disposed bevel gear 27, which is also relatively rotatably received on the shaft 21, the gears 26 and 27 being mounted on the shaft so as to be relatively non-shiftable, but to permit relative axial shifting of the shaft, and an idler bevel gear 28 is mounted in the box to be in constant meshing engagement with said spaced bevel gears. Fixed on the shaft 21 may be a clutch member 30 having oppositely toothed faces adapted to be engaged with one or other of reciprocally toothed portions 31 and 32, integral with the bevel gears 26 and 27, respectively. That is, the shaft 21 is axially shiftable rearwardly of the machine into clutching engagement of the member 30 with the clutch portion 31, whereby the bevel gear 26 will be in direct driving connection with the shaft 21 to rotate the drum 10 in one direction. Similarly, by shifting the shaft 21 forwardly of the drum, to engage clutch member 30 with the clutch portion 32, the shaft will be driven in reverse direction indirectly through meshing engagement of the idler gear 28 with the gears 26 and 27.

Mounted forwardly of the pulley 17 may be a self-operating reversing and indexing mechanism, indicated generally at 35, the same including a bracket 36 suitably supported on base 13, as by means of an upright 37, the bracket 36 having spaced lugs 38 and 39 provided with aligned apertures for receiving therethrough a forward extension of shaft 21. An element or quadrant 42 may be suitably mounted on shaft 21, as in the manner indicated generally at 40 (see Figures 1 to 5), to be relatively rotatable but axially relatively non-shiftable thereon, the quadrant extending toward the drum 10, in a plane at right angles to the axis thereof. The arrangement is such that shaft 21 may rotate continuously in either direction independently of relatively fixed or partially rotated positions of the quadrant 42, as will be described later. The outer edge portion of the quadrant 42 is arcuately shaped and is provided with a plurality of arcuately spaced recess portions 43, 44, 45 and 46, the recesses being shaped like a gear tooth and there being one more recessed portion than the desired number of revolutions of drum 10 in either direction. Secured

to the outer surface of the drum 10, to be aligned with quadrant 42 in any axially shifted position thereof, may be an elongated protuberance 47 which is shaped on the order of a gear tooth and adapted to mesh with the recesses of the portions 43 to 46, in a manner to be described.

A hub portion 49 of the quadrant 42, through which the shaft 21 is received, may be cylindrical in shape and is provided on an unobstructed cylindrical surface portion thereof with transversely extending slots 50 and 51, which are adapted releasably and slidably to receive a spring-pressed detent 52 mounted in a boss 53 in the bottom portion 54 of the bracket 36. The slots 50 and 51 are in locations corresponding to extreme limits of angular movement of the quadrant 42, as illustrated in full lines in Figures 2 and 5. Intermediate the slots 50 and 51, at the unobstructed side of the hub 49, may be two transversely spaced series of circumferentially spaced recesses 57 for receiving detent 52 (see Figure 3), the location of these recesses with respect to the slots 50 and 51, corresponding to the progressively advanced positions of the quadrant as urged by the tooth 47, and the spaced series being arranged to be in alignment with the detent in both axially shifted positions of the quadrant. Lip extensions 55 and 56 from the bracket 36 are provided for engagement by the opposite ends of the outer arcuate portion of the quadrant, in said extreme positions thereof shown in Figures 2 and 5. This arrangement is such that in the full line position of the quadrant shown in Figure 2 rotation of the drum 10 in counter-clockwise direction, for example, will cause the tooth 47 thereon to mesh with the recess of portion 46 of the quadrant for a short distance of angular movement of the drum, thereby to swing the quadrant in clock-wise direction to the chain-dotted position shown in Figure 2. Upon the next three full rotations of the drum the tooth 47 will successively mesh with the recesses of portions 45, 44 and 43 progressively to advance the quadrant to the extreme full line position thereof of Figure 4, the quadrant being releasably held in each intermediate position by yielding engagement of the detent 52 in recesses 57 of one series thereof (see Figure 3), and then in the extreme position of Figure 4 by engagement of the detent in slot 50.

Referring particularly to Figures 4 and 5, immediately after the tooth 47 moves the quadrant 42 from the chain-dotted to the full line position thereof of Figure 4, which is at the end of the third successive rotation of the drum in counter-clockwise direction, an angularly spaced cam plate 58, mounted on the surface of the drum in clockwise circumferentially spaced relation to the tooth 47, will engage a roller 59 mounted at the adjacent end of the arcuate portion of the quadrant 42 at the rear side thereof, to shift the quadrant 42 forwardly of the drum from the full-line to the chain-dotted position shown in Figure 5. This shifting movement of the quadrant correspondingly shifts the shaft 21 forwardly to engage clutch member 30 with clutch portion 32, to drive the shaft in the opposite direction and thereby correspondingly to reverse the operation of the drum. With this shifting movement of the quadrant, the detent 52 in sliding engagement in the slot 50 will become aligned with the other series of recesses 57 for the next succession of revolutions of the drum 10 in reverse direction. When the drum, as viewed in Figure 4, is reversed to rotate in counter-clockwise direction

the tooth 47, at the beginning of a first revolution of the series thereof, will move the quadrant 42 from the full-line position of Figure 4 to the chain-dotted position therein, and with each succeeding rotation of the drum in the same direction the tooth will progressively move the quadrant in counter-clockwise direction in the manner previously described, until it is advanced to the full-line position shown in Figure 2. Immediately after the tooth 47 leaves the recess of portion 46, moving in counter-clockwise direction, a cam plate 58a which is disposed oppositely to the cam plate 58, both forwardly and circumferentially of the tooth 47, will engage a roller 60 mounted at the other extreme end of the outer arcuate portion of quadrant 42 and on the side opposite from roller 47. This will shift the quadrant and the shaft 21 axially to the full-line position of the quadrant shown in Figure 1. In the last-named position the clutch member 38 is moved to engage clutch portion 31 to again reverse the rotation of the shaft. Thus after each third successive rotation of the drum 10, in either direction, it is self-operating through the quadrant 42 to reverse the direction of rotation.

In the operation of the machine for treating clothes, the clothes to be treated are placed in the drum 10 through the closure means 16 at the front of the drum, and the motor 20 is then started to drive the drum 10 in one direction through the gear mechanism in box 19. As previously described three full revolutions of the drum 10 in counter-clockwise direction will move the quadrant 42 from the full-line position of Figure 2 to the full-line position of Figure 4, and immediately thereafter the cam 58 on the drum will engage roller 59 on the quadrant, as shown in full lines in Figures 4 and 6, to shift the quadrant forwardly of the drum to the chain-dotted line position thereof shown in Figures 5 and 6. This forward movement of the quadrant 42 will shift the clutch member 30 to reverse the rotation of the drum 10, and the tooth 47 similarly successively meshing with the recessed portions 43 to 46 will progressively advance the quadrant back to the full-line position shown in Figure 2, when the cam 58 will engage roller 60 to shift quadrant and shaft 21 rearwardly to operate the clutch for another reversing movement of the drum. Continuous operation of the motor 20 will drive the drum in successive series of three revolutions in opposite directions for effective tumbling of the clothes being treated therein, and with a minimum of tangling the clothes.

Thus has been provided a relatively simple reversing mechanism for a washing machine, which is self-operating by rotation of the drum in either direction for reversing the rotation of the drum. It is understood that the number of successive rotations of the drum in one direction may be as desired by correspondingly changing the number of tooth-receiving recessed portion on the quadrant 42. It is also understood that modifications of the invention may be resorted to without departing from the spirit thereof or the scope of the appended claims.

What is claimed is:

1. A machine of the character described, comprising: a relatively fixed support, a member rotatably mounted on said support, a power shaft journaled in association with said member, driving power means, a reversing mechanism between said power means and said power shaft, power transmission means between said power shaft

and said rotatable member to rotate the same, interengageable indexing means on said rotatable member and said power shaft, said indexing means including an element axially shiftable with respect to said axis of said shaft and transversely shiftable with respect thereto progressively with successive revolutions of said member, and interengageable means on said member and said element engageable after a predetermined transverse shifting of said element in either direction to shift said element in corresponding axial direction and thereby through said reversing mechanism to reverse the drive of said power transmission means.

2. A machine of the character described, comprising a relatively fixed support, a drum rotatably mounted on said support, a power shaft journaled in association with said rotatable drum, driving power means, a reversing mechanism between said power means and said power shaft, power transmission means between said shaft and said rotatable drum, interengageable indexing means on said rotatable drum and said power shaft, said indexing means including an element axially shiftable with respect to the axis of said shaft and transversely shiftable with respect thereto progressively with successive revolutions of said drum, and interengageable means on said drum and on said element engageable after predetermined transverse shifting of said element in either direction to shift said element in corresponding axial direction and thereby through said reversing mechanism to reverse the drive of said power transmission means.

3. A machine of the character described, comprising a relatively fixed support, a drum mounted on said support to be rotatable about an axis, a power shaft axially shiftably mounted in association with said rotatable drum, driving power means, a reversing mechanism between said power means and said power shaft operable to rotate the same in opposite directions by axially shifting said power shaft, power transmission means between said shaft and said rotatable drum, interengageable indexing means on said rotatable drum and said power shaft, said indexing means being interengageable whereby upon a predetermined number of revolutions of said rotatable drum in either direction said power shaft is axially shifted in one direction or the other and whereby through said reversing mechanism said power transmission means is correspondingly reversed in driving direction, said indexing means including a tooth on said rotatable drum to rotate therewith in an arcuate path, an element shiftably mounted on said power shaft to extend toward the path of movement of said tooth and having a plurality of arcuately spaced tooth-receiving portions, whereby with each rotation of said drum said tooth is engageable with successive tooth receiving portions progressively to shift said element, in direction transversely of said axis of said power shaft, and means operable upon predetermined progressive axial shifting of said element by said tooth in either direction to provide said reversing transverse shifting movement of said power shaft.

4. A machine of the character described, comprising a relatively fixed support, a member mounted on said support to be rotatable about an axis, a power shaft shiftably mounted in association with said member, a driving power means, a reversing mechanism between said

power means and said power shaft operable to rotate the same in opposite directions by axially shifting said power shaft, power transmission means between said power shaft and said rotatable member to rotate the same, interengageable indexing means on said rotatable member and said power shaft, said indexing means being interengageable upon a predetermined number of revolutions of said rotatable member in either direction, said power shaft being axially shifted in one direction or the other and whereby through said reversing mechanism said power transmission means correspondingly reversed in driving direction, said indexing means including a tooth on said rotatable member to rotate therewith in an arcuate path, an element shiftably mounted on said power shaft to extend toward the path of movement of said tooth and having a plurality of arcuately spaced tooth-receiving portions, whereby with each rotation of said member said tooth is engageable with successive tooth receiving portions progressively to move said element in a direction transversely of said axis of said power shaft, and cam means on said member and said element operable upon said predetermined progressive transverse shifting of said element in either direction to provide said reversing axial shifting movement of said power shaft.

5. In apparatus of the character described, the combination with a rotatable member, means for mounting said member to rotate about an axis, power means including a reversing mechanism for rotating said member in either direction, of indexing means to control the direction of rotation of said member comprising a protrusion on said member and rotatable therewith in a path of movement about said axis, an element transversely shiftably and pivotally mounted to extend toward said path of movement of said protrusion and having a plurality of arcuately spaced portions for successive meshing engagement by the protrusion as the member is rotated progressively to advance said element about the pivot thereof, spring-pressed detent means for yieldingly retaining said element in said progressively advanced positions thereof, said element including a cylindrical part having arcuately spaced transversely extending slots and two transversely spaced series of arcuately spaced recesses intermediate said slots for receiving said detent, stop means for limiting pivotal movement of said element in both directions, cam means on said member and said element for transversely shifting the element in opposite directions upon engagement of said detent in one of said slots, and means controlled by said transverse shifting of said element to operate said reversing mechanism.

6. In apparatus of the character described, the combination with a rotatable member, means for mounting said member to rotate about an axis, power means including a reversing mechanism for rotating said member in either direction, of indexing means to control the direction of rotation of said member comprising a protrusion on said member and rotatable therewith in a path of movement about said axis, an element transversely shiftably and pivotally mounted to extend toward said path of movement of said protrusion and having a plurality of arcuately spaced portions for successive meshing engagement by the protrusion as the member rotated progressively to advance said element about the pivot thereof, means for yieldingly retaining said

element in said progressively advanced positions thereof, said element including a cylindrical part having arcuately spaced transversely extending slots and two transversely spaced series of arcuately spaced recesses intermediate said slots for receiving said detent, stop means for limiting pivotal movement of said element in both directions, cam means on said member and said element for transversely shifting the element in opposite directions upon engagement of said detent in one of said slots, and means controlled by said transverse shifting of said element to operate said reversing mechanism.

7. In apparatus of the character described, the combination with a rotatable member, means for mounting said member to rotate about an axis, power means including a reversing mechanism for rotating said member in either direction, of indexing means to control the direction of rotation of said member comprising a protrusion on said member and rotatable therewith in a path of movement about said axis, an element transversely shiftably and pivotally mounted to extend toward said path of movement of said protrusion and having a plurality of arcuately spaced portions for successive meshing engagement by the protrusion as the member rotated progressively to advance said element about the pivot thereof, spring-pressed detent means for yieldingly retaining said element in said progressively advanced positions thereof, stop means for limiting pivotal movement of said element in both directions, cam means on said member and said element for transversely shifting the element in opposite directions in said positions of limited pivotal movement of the element, and means controlled by said transverse shifting of said element to operate said reversing mechanism.

8. In apparatus of the character described, the combination with a rotatable member, means for mounting said member to rotate about an axis, power means including a reversing mechanism for rotating said member in either direction, of indexing means to control the direction of rotation of said member comprising a protrusion on said member and rotatable therewith in a path of movement about said axis, an element transversely shiftably and pivotally mounted to extend toward said path of movement of said protrusion and having a plurality of arcuately spaced portions for successive meshing engagement by the protrusion as the member rotated progressively to advance said element about the pivot thereof, spring-pressed detent means for yieldingly retaining said element in said progressively advanced positions thereof, cam means on said member and said element for transversely shifting the element in opposite directions in said positions of limited pivotal movement of the element, and means controlled by said transverse shifting of said element to operate said reversing mechanism.

spaced portions for successive meshing engagement by the protrusion as the member rotated progressively to advance said element about the pivot thereof, means for yieldingly retaining said element in said progressively advanced positions thereof, cam means on said member and said element for transversely shifting the element in opposite directions in said positions of limited pivotal movement of the element, and means controlled by said transverse shifting of said element to operate said reversing mechanism.

9. In apparatus of the character described, the combination with a rotatable member, means for mounting said member to rotate about an axis, power means including a reversing mechanism for rotating said member in either direction, of indexing means to control the direction of rotation of said member comprising a protrusion on said member and rotatable therewith in a path of movement about said axis, an element transversely shiftably and pivotally mounted to extend toward said path of movement of said protrusion and having a plurality of arcuately spaced portions for successive meshing engagement by the protrusion as the member rotated progressively to advance said element about the pivot thereof, spring-pressed detent means for yieldingly retaining said element in said progressively advanced positions thereof, cam means on said member and said element for transversely shifting the element in opposite directions in said positions of limited pivotal movement of the element, and means controlled by said transverse shifting of said element to operate said reversing mechanism.
